UNITED STATES PATENT OFFICE.

CLAUDE WHITE, OF ST. LOUIS, MISSOURI, ASSIGNOR OF ONE-HALF TO
CHARLES T. NOLAND, OF ST. LOUIS, MISSOURI.

SIGNAL SYSTEM.

SPECIFICATION forming part of Letters Patent No. 781,319, dated January 31, 1905.

Application filed February 2, 1904. Serial No. 191,763.

To all whom it may concern:

Be it known that I, CLAUDE WHITE, a citizen of the United States, residing at St. Louis, State of Missouri, have invented certain new and useful Improvements in Signal Systems, of which the following is a specification containing a full, clear, and exact description, reference being had to the accompanying drawings, forming a part hereof.

10 My invention relates to improved signal systems, my object being to provide an effective signal system whereby signals may be conveyed to trainmen on a running train wherever the train may be; and my improved 15 signal system comprises a series of lights arranged along a railway and directed within the plane of vision of the trainmen, said lights being normally out of operation, and means of illuminating said lights for the purpose of 20 signaling the trainmen.

In the drawings, Figure 1 is a diagrammatic view showing a signal system embodying the principles of my invention. Fig. 2 is a view in elevation, showing the signal-light directed into the cab of the locomotive within the plane of vision of the engineer and other trainmen. Fig. 3 is an enlarged detail of the light and post.

Referring to the drawings in detail, a series of posts 4 is arranged along the railway 5, and an electric wire 6 is strung on said posts, one end of said wire terminating at the light 7 in the station 8 and the other end of said wire terminating at the light 9 in the station 10. A similar wire 11 leads from the light 12 in the station 8 to a similar light in the next station up the railway, and another similar wire 13 leads from the light 14 to a similar light in the next station down the railway. The lights 15 are mounted upon the posts 4, arranged along the railway between the stations 8 and 10, each of said lights being connected to the wire 6, and similar lights 16 and 17 are connected to the wires 11 and 13, respectively.

The generator 18 may belong to the street-car or lighting plant of the town in which the station 8 is located, and said generator is con-

nected to the switches 19 and 20, and said switches are connected to the wires 6 and 11, respectively. The generator 21 may belong to the street-car or lighting plant of the town in which the station 10 is located, and said generator is connected to the switches 22 and 23, said switches being connected to the wires 6 and 13, respectively.

The lights 15, 16, and 17 are constructed as shown in detail in Fig. 3. Brackets 24 are attached to the posts 4, and semi-oval shells 25 are secured to the brackets. The lamp-base 26 is secured in the apex of the shell, and the wires lead through this base. The light-fixture 27 is attached to this base 26, a reflector 28 is mounted in the shell 25, and the bulb 29 occupies a central position in front of the reflector, being connected to the fixture 27 through the reflector 28. A heavy concavo-convex glass plate 30 is placed in the open end of the shell 25, and the edge 31 of the shell is turned in to hold the glass. The fixture thus 70 constructed produces a concentrated shaft of light 32, like a search-light, and the fixtures are so mounted on the posts as to direct the shafts of light into the line of vision of the trainmen. The light-fixtures are preferably 75 mounted on a level with the windows of the locomotive-cab, so that the shafts of light will cross the path of the locomotive and strike the eyes of the engineer and fireman and pass through the car-windows and attract the attention of the passengers, as well as of the trainmen.

In my signal system each station is independently connected with the next adjoining station in both directions, so that any piece 85 of track between the two stations is protected by the signal system from both ends. The light may be red or white or of any desired color, and the power may be derived, as before suggested, from the local plants of the 90 towns in which the stations are located, or, if preferred, generating plants may be maintained exclusively for the purpose of operating my signal system. The lights in the stations are intended to show the operators when 95 the signals are in operation. A code of flash-

light signals may be arranged so that the operators may communicate any desired information to the trainmen.

I claim—

- 5 In a signal system: a series of stations; a series of posts arranged along a railway between the stations; an electric wire strung on the posts between two stations; a light at each end of the wire; lights on the posts connected 10 to the wire and grounded; and a generator at

each station, so that the lights may be illuminated from either end; substantially as specified.

In testimony whereof I have signed my name to this specification in presence of two 15 scribing witnesses.

CLAUDE WHITE.
